IMPLANTABLE MEDICAL-ELECTRONIC CARDIAC PACER UNIT

Howard J. Thompson, New Richmond, Wis., assignor to Medtronic, Inc., Minneapolis, Minn.

Filed Apr. 26, 1974, Ser. No. 464,487

Term of patent 14 years

Int. Cl. D24—03

U.S. Cl. D83—1 F

Fig. 1

Fig. 2

Fig. 3

Fig. 4

Fig. 5

Fig. 6

Fig. 7

FIG. 1 is a front view in perspective of an implantable medical-electronic cardiac pacer unit, showing my new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top elevational view thereof; and

FIG. 7 is a bottom elevational view thereof.

I claim:

The ornamental design for an implantable medical-electronic cardiac pacer unit, as shown.
